US00D771999S

(12) **United States Design Patent** (10) Patent No.: **US D771,999 S**
 (45) Date of Patent: **** Nov. 22, 2016**

(54) **BLENDER BASE**

- (71) Applicant: **Vita-Mix Corporation**, Olmsted Township, OH (US)
- (72) Inventors: **Phonesacksih Guy Kettavong**, Kent, OH (US); **Jack Warren Gee, II**, Willoughby, OH (US); **Kolman Juhasz**, Pama, OH (US); **Eugene J. Kozlowski**, Medina, OH (US); **David A. Kanning**, Valley City, OH (US); **Michael Patrick Arnett**, Columbia Station, OH (US); **Richard Joseph Lash**, Avon Lake, OH (US)
- (73) Assignee: **Vita-Mix Management Corporation**, Olmsted Township, OH (US)
- (**) Term: **14 Years**
- (21) Appl. No.: **29/485,013**
- (22) Filed: **Mar. 14, 2014**
- (51) LOC (10) Cl. **31-00**
- (52) U.S. Cl. USPC **D7/386**; D7/376; D7/378; D7/412

(57) **CLAIM**

The ornamental design for a blender base, as shown and described.

DESCRIPTION

FIG. 1 is a perspective view of a blender base showing our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines in the figures are included for the purpose of illustrating portions of a blending base and form no part of the claimed design.

1 Claim, 4 Drawing Sheets(56)
